UNITED STATES PATENT OFFICE

159,412

CABINET FOR PRINTING PLATES

Robert L. Franklin, San Francisco, Calif., assignor
to Benjamin S. Ebersole, San Francisco, Calif.

Application February 18, 1949, Serial No. 934

Term of patent 7 years

(Cl. D64—11)

To all whom it may concern:

Be it known that I, Robert L. Franklin, a citizen of the United States, residing in the city of San Francisco, county of San Francisco, and State of California, have invented a new, original, and ornamental Design for a Cabinet for Printing Plates, of which the following is a specification, reference being had to the accompanying drawings, forming a part thereof.

Fig. 1 is a front perspective view of a cabinet for printing plates, showing my new design; Fig. 2 is a rear perspective view, and Fig. 3 is a top plan view of the same.

I claim:
The ornamental design for a cabinet for printing plates, as shown.

ROBERT L. FRANKLIN.
